UNITED STATES PATENT OFFICE

96,443

DESIGN FOR A BRACELET OR SIMILAR ARTICLE OF JEWELRY

Leo Bojar, Providence, R. I.

Application June 26, 1935, Serial No. 57,406

Term of patent 3½ years

To all whom it may concern:

Be it known that I, Leo Bojar, a citizen of the United States of America, residing in Providence, county of Providence, State of Rhode Island, have invented a new, original, and ornamental Design for a Bracelet or Similar Article of Jewelry, of which the following is a specification, reference being had to the accompanying drawing, forming a part thereof.

Fig. 1 is an edge view of a bracelet or similar article of jewelry, and Fig. 2 is a plan view of one of the curved sections in a single plane to illustrate its design without distortion of the same.

I claim:

The ornamental design for a bracelet or similar article of jewelry, substantially as shown and described.

LEO BOJAR.
